DESIGN FOR AN UNDERGARMENT

Mae O'Gorman and Maud E. O'Gorman,
Los Angeles, Calif.

Application April 5, 1939, Serial No. 84,047

Term of patent 14 years

To all whom it may concern:

Be it known that we, Mae O'Gorman and Maud E. O'Gorman, both citizens of the United States, residing in Los Angeles, in the county of Los Angeles and State of California, have invented a new, original, and ornamental Design for an Undergarment, of which the following is a specification, reference being had to the accompanying drawing, forming part thereof.

Fig. 1 is a perspective view of the undergarment from the left rear showing my new design; and

Fig. 2 is a perspective view of the undergarment from the right front.

We claim:

The ornamental design for an undergarment, as shown.

MAE O'GORMAN.
MAUD E. O'GORMAN.
